OVERCORRECTIVE SHOE FOR TALIPES
VARUS

William O. Minor, Atlanta, Ga., assignor to Dorothy C. Minor, Atlanta, Ga.

Application July 27, 1939, Serial No. 286,745

1 Claim. (Cl. 36—8.5)

This invention relates to an overcorrective shoe for talipes varus, commonly known as club foot.

The principal object of the present invention is the provision of a shoe for the correction of talipes varus in which the principal deformation is in the rear part of the foot, particularly in the region of the ankle bones and os calcis. In my co-pending application, Serial No. 286,061, filed July 24, 1939, I have disclosed and claimed an overcorrective shoe for talipes varus in which the principal deformation is in the forward part of the foot.

In the treatment of talipes varus, it is common practice to keep the deformed foot in a cast for a relatively long period of time during which the bones, muscles and ligaments are rigidly held in a corrective position. When the cast has been removed, there is a tendency for the foot to return to the original deformed condition unless corrective shoes are applied. This tendency is so marked that a normally shaped shoe fails to hold the foot in the normal position and for that reason I have found it advantageous to provide shoes which overcorrect the deformity. The degree of overcorrection necessary depends upon the original degree of deformity of the foot, the nature of the deformity and the extent of the correction which has been secured by treatment in the cast.

Other objects and features of the invention will be understood from the accompanying drawing and the following description and claim. Since the form of a shoe follows closely the form of the last on which it is made, the shape of the shoe is best described with reference to the last. Several of the figures, therefore, show the last rather than the shoe.

Fig. 1 is a plan view of a preferred form of last on which a shoe may be built in accordance with the invention. Fig. 2 is a rear view thereof with certain parts of the shoe added thereto. Fig. 3 is a vertical sectional view taken on the line 3—3 of Fig. 1 with the insole added thereto. Fig. 4 is a rear view of a shoe constructed on the last illustrated.

The deformation known as talipes varus consists of an inward turning of the forepart of the foot and an outward rolling of the ankle such that the outer toes and outer edge of the foot are lowermost. To provide a correction for this condition, the last 10 shown in Fig. 1, and consequently the shoe formed on said last, is formed with the axis A—B of the forepart of the foot inclined outwardly with respect to the axis A—C of the heel portion. This outward inclination of

the axis of the forepart is technically known as "abduction."

To provide an overcorrection, in cases in which the principal deformation is in the heel portion of the foot, the last is formed as best shown in Fig. 2 with the undersurface 11 of the heel portion upwardly and outwardly inclined with respect to the undersurface of the forward portion, the relative position of which is indicated by the broken line D—E. The heel axis F—G is inclined inwardly from the vertical. The line F—G represents the extreme rear surface of the heel of the last and in normal shoes is substantially vertical.

15 In constructing a shoe on this last, a wedge piece 12 having the horizontal extent indicated in Fig. 1 is applied to the heel of the insole 13 between the same and the last. The outer corner 14 of the last is rounded and the wedge piece is provided with a lip 15 closely fitting the curvature of the last. In Fig. 2 the undersurface of the heel of the finished shoe is indicated by the broken line 16. In the forward part of the shoe as shown in Fig. 3 the lower surface of the last 10 is substantially straight across or slightly rounded in the downward direction as in normal shoes. The interior foot bearing surface of the forward part of the shoe is thus substantially parallel to the undersurface of the outsole indicated in Fig. 3 by the broken line 17.

In a shoe constructed on the last just described and shown in Fig. 4, the rear portion of the shoe is inclined inwardly with respect to the undersurface of the heel. The inner foot bearing surface of the heel portion represented by the upper surface of the wedge 12 and insole 13 is inclined upwardly and outwardly with respect to the undersurface of the heel of the shoe. This construction gives to the heel portion of the foot an outward twist with respect to the ankle which when combined with the abducted forward portion of the shoe provides an overcorrection resisting the tendency of the ankle to roll outwardly and to return to its original deformed condition.

The provision of the rounded corner 14 of the last and the accompanying lip on the wedge piece prevents the heel of the foot from running over the edge of the wedge piece and insole and pressing unduly on the upper. It thus serves to preserve the form of the shoe and prevents callouses forming on the side of the foot at this point.

The shape of the shoe constructed in accordance with the invention has been indicated by describing the last on which it is made. Con-

structural features of the shoe which distinguish from the usual practice have been illustrated. In other respects, normal shoe making practice is followed and need not be described in detail. The details of the invention as herein disclosed may be varied without departing from the scope thereof as defined in the appended claim.

The invention claimed is:

An overcorrective shoe for talipes varus having the forward portion materially abducted, having the interior foot bearing surface of the forward part substantially parallel with the plane of the undersurface of the outsole, and the interior foot bearing surface of the heel portion upwardly and outwardly inclined with respect to said plane.
